Claims priority, application France June 29, 1957

4 Claims. (Cl. 53—184)

The present invention relates to packaging and similar machines of the kind intended to permit the formation of articles, especially boxes and similar containers, from flexible bands of a material such for example as a thermoplastic material of the type of vinyl chlorides, polyethylenes, polyamides, etc.

Machines of this kind have already been described, for example in United States Patent No. 2,736,150 granted on February 28, 1956, but these machines have a very high production cost and only permit of the production of a single type of article, which makes it impracticable to employ them industrially for the manufacture of small and medium sizes of a single article.

The present invention has as an object the provision of a machine for making articles of plastic material which satisfies, better than any other available up to the present time, the various requirements of practice, especially with respect to their low cost of production and their universal nature (the aptitude of a single machine, with slight modifications in some cases, for the manufacture of very different types of articles).

The invention mainly consists in arranging the machines of the kind referred to in such manner that at least one band can be brought through a number of units or stations (for heating, forming, welding, cutting-out) arranged in succession in positions which are preferably variable at will so as to be adapted to the manufacture envisaged, these units being preferably mounted in an adjustable manner on at least two parallel bars, and comprising in most cases a portion in the form of a gantry adapted to be fixed in an adjustable manner on these bars, and a movable portion of annular form displaceable with respect to the gantry portion perpendicular to the band, the whole being in combination with means for moving the band step by step at a rhythm which is a function of the cycle of operations effected in the said units.

In the preferred embodiment of the invention, the machine comprises a station for heating the band before forming, which comprises means such as masks which enable the extent and/or the position of the zone of the band to which the heating is applied, to be varied at will.

The invention will be more readily understood by reference to the description which follows and to the accompanying drawings, the said description and drawings being understood to be given by way of example only.

In the drawings:

FIG. 1 is a diagram in elevation of a machine, provided in accordance with the invention, capable of manufacturing boxes;

FIG. 2 is a diagrammatic view in perspective of a machine according to the invention, corresponding to the diagram of FIG. 1;

FIGS. 3 to 5 show in side view and partly in cross-section, the units or stations of the machine of FIG. 2 for respectively forming, welding and cutting-out operations;

FIGS. 6 and 7 respectively show diagrammatically, in vertical cross-section and in plan view, the heating device which is also comprised in the said machine;

FIGS. 8 and 9 show a perspective view of a band treated in two different ways by means of a machine provided in accordance with the invention;

2

FIG. 10 shows in perspective a box with an attached handle, capable of being produced by means of such a machine;

FIG. 11 shows in perspective another type of box or receptacle which can be produced by means of a machine according to the invention;

FIG. 12 shows a perspective view of a further article, mainly a bottle, obtained with a machine in accordance with the invention;

10 FIG. 13 shows also in perspective a similar article obtained from two bands;

FIG. 14 shows in perspective an article of the type of teacloths with embroidery, produced by the said machine;

15 FIG. 15 shows in perspective the manufacture of articles of the wallet type;

FIG. 16 is a detailed view in perspective of a machine according to the invention, in conformity with the diagrammatic views of FIGS. 1 and 2;

20 FIG. 17 is a perspective view of the device of FIG. 16; and

FIG. 18 is a diagrammatic view of an alternative form of the machine of FIGS. 1, 2 and 16.

The invention contemplates a machine which is arranged in such a manner that it permits of continuous treatment of at least one band which is brought successively, by means of a step-by-step mechanism regulated according to the nature and the time-cycle of the operations to be effected, through a number of units or stations comprised by the said machine and adapted in particular;

To insure the previous heating of the said band at the place or in proximity to the place at which the forming is to be effected;

25 35 Then to carry out this forming, preferably by a pneumatic action, and in particular by the action of a vacuum created in an appropriate mould;

To enable the cavities obtained by this forming operation to be eventually filled in the case of boxes;

40 45 To insure, if desired the superposition and the fixing of a surface adapted to co-operate with the first, especially so as to form a cover or lid;

And again in the case of boxes, to enable these to be cut-out and ejected from the initial band or bands;

50 55 It being understood that the nature and the succession of the operations may be other than those which have just been indicated, since they will depend on the applications considered.

Generally speaking, the said units or stations are preferably arranged in accordance with the invention in such manner that their respective positions may be regulated, especially in order to enable the machine to be adapted to very different operations.

60 65 To take an example, and assuming the case of manufacture of boxes with lids, the machine of FIG. 1 is arranged so that it carries out simultaneous treatment of two bands 1 and 2 intended respectively for the box and for the lid, and unwinding step-by-step from reels 3 and 4, these bands being particularly treated in the stations following in succession along the machine, at intervals of respective lengths A, B, C, D, E, F, which can be varied at will:

At A is provided a heating station CH, for example operating by infra-red rays, this station being preferably adjustable and especially according to the arrangement described later with reference to FIGS. 6 and 7, in such manner that the dimensions of the surface to be heated can in particular be selected at will;

70 At B is provided a forming station PF, comprising essentially a mould 5 with holes 6 or other means of creating a vacuum and thus treating the band so as to

take the shape of the mould, producing a formed band 1a;

At C is provided a free space corresponding to a filling zone, with manual or automatic filling means the said space being of variable length, that is to say comprising a variable number of elementary lengths d , depending on the requirements of the filling stage;

At D is provided a welding station PS to fit and fix the lid (or other member) produced from the second band 2, on the formed band 1a, it being understood that the closure may be wholly or partly sealed and that this closure may be combined with any other operation such as evacuating or filling with gas;

At E is provided a punching-out and ejection station PD, when boxes such as 7 are to be produced;

And at F is provided a drawing device Ti, that is to say adapted to cause the band or the two bands or more to progress step by step at a suitable rate so as to pass them from one station to that following.

In FIG. 2, and especially in FIG. 16 (in which the same reference numbers have been used for the same elements), there has been shown in somewhat greater detail a machine which complies with the conditions which have just been stated. It can be seen that the pull from the drawing device Ti is applied on the portions 8 of the bands which remain after cutting-out and ejection. This device could however be the ejector device in the case where the finished products consist of bands shaped in a suitable manner (such as for example the cases of FIGS. 8, 9, 13, etc., which will be described later). For a filling operation in the case of boxes, a dosing device is mounted at 19.

With regard to the manner of construction of the various stations or units CH, PF, etc., referred to above, this may be carried out in different ways, especially having regard to the arrangements which will now be examined.

In the first place, according to a general arrangement which can be applied to the whole of the machine, the construction is such that the various stations are mounted in an adjustable manner on at least two bars or similar means such as 9 (FIGS. 2 and 16), this arrangement enabling the respective positions of the said stations to be regulated in a very simple manner by sideways displacement of the said bars (in FIG. 16 there is shown a graduated rule 35 which serves for the correct positioning of the various movable stations).

Then as regards the stations themselves, and in the first place with reference to the heating station CH, the latter is arranged in such manner that it comprises various masks and screens, the positions of which can be varied so as to permit the size and/or the position of the surface to be heated to be varied at will; and to form, especially on the edges of the bands, marginal reserved portions which are not subjected to heating with the object of leaving the remaining portions such as 8 (FIGS. 2 and 16) in the case where cutting-out is provided, with a suitable strength to withstand the tractive effort to be applied by Ti.

In accordance with the embodiment shown in FIGS. 6 and 7, it has been assumed that four screens are arranged to co-act with rows of infra-red heaters 10, namely:

Two screens 11 cooled by water circulation or other means, these screens being adapted to mask a variable fraction of the field of action of the said rows, and thus to regulate the total surface to be heated (that is to say, in the case shown, the surface of the box to be formed, shown as a shaded surface in FIG. 7);

And two further screens 12 acting laterally so as to provide the marginal reserves referred to above, so that the band can retain on its edges its initial mechanical characteristics.

In FIG. 16, there can be seen on the one hand the

two lateral screens 12 which leave unheated the edges of the band 1, the distance apart of these two screens being adjustable so as to be able to treat bands of different widths, and on the other hand, the single screen

5 11 arranged underneath the band 1 (since the heating of the band takes place solely from below in the case of this machine), the position of this screen 11 being adjustable by means of a lever 11a by pulling it more or less out of the heating device CH.

10 As regards the other stations concerned with the operations of forming, welding, cutting-out, etc., these are preferably produced:

By a portion 13, especially in the form of a gantry, adapted to be fixed in an adjustable manner on the bars 9;

And by a plate 14 movable transversely with respect to the band to be treated (in this case vertically), guided for example by means of columns 15, this plate being preferably in the form of an elongated ring, the working 20 tools for forming, welding, and cutting-out being respectively carried by these two portions 13 and 14.

The ring form of the plates such as 14 is an advantage in effecting the mounting and positioning of the forming, welding and cutting-out tools. In addition, in the cutting-25 out station, it facilitates the ejection of the box or other article 7, which passes out through the interior of the said ring and thus reaches the ejection hopper 24 (see FIGS. 2 and 5).

The operations of forming, welding, cutting-out and the 30 like, will be effected with advantage by movements of the movable plate 14. In any case, the latter should generally be moved away from the corresponding gantry after each operation, if this displacement is necessary to permit the continued travel of the band. For the movement 35 of the said plate 14, any known means may be employed, for example the jacks 16 operated by compressed air.

In FIG. 16 there has been shown a preferred form 40 of embodiment employing the simultaneous distribution of compressed air through an incoming conduit 37 and a return conduit 38, to the three jacks 16 of the forming station PF, the welding station PS and the cutting-out station PD in order that these three operations of forming, welding and cutting-out may be carried out simultaneously 45 when the band is stopped.

FIG. 3 shows the forming station. There can be seen at 17 a fixed base carried by the gantry 13 and at 5 the mould proper with its conduits 6 connected at 18 to the source of vacuum, this source being constituted for example by a vacuum pump driven by compressed air.

In certain cases, the forming station PF may simply produce surface effects or cut-out portions for example, so as to produce articles such as those shown in FIGS. 14 and 15.

55 FIG. 4 shows the welding station (with the fixed electrodes 21 carried by the portion 13) and the moving electrode 20 carried by the annular plate 14.

FIG. 5 shows the cutting-out station, the respective tools being shown at 22 (the moving tool carried by the 60 annular plate 14) and at 23 which is the fixed tool carried by the gantry 13.

When the manufacture is changed, it is only necessary to modify the working tools 5—17, 20—21, 22—23, and to move the masks 11 and 12 together with the stations 65 themselves, which can be effected very rapidly. In order to carry out a new manufacture, it is generally only necessary to provide new working tools, which is very economical.

As far as the drawing device such as Ti is concerned, this can be produced in a number of ways.

In FIGS. 1 and 2, it has been assumed that this device was constituted by the assembly of two pieces, namely: a member 25 forming a support, this member being fixed in an adjustable manner on the bars 9 and carrying actuating means such as a jack 26; and a gripping member 27

which can be mounted freely on the said bars while being actuated by the jack 26, the said member comprising gripping elements such as two bars or rollers 28 and 29, between which the band or bands are passed.

These two small bars are normally urged towards each other so as to grip the bands. During the operation of the jack 26, the latter moves the member 27 in the direction *f* and also draws the bands with it. A tension stress (by weights, etc.) may be applied at the outlet of the machine on the said bands, which in addition may be led between guiding rollers 30 and 31. On the return movement of the jack, an electro-magnet device or the like (not shown) momentarily moves the gripping bars 28 and 29 apart, so that the latter, when the recoil movement is complete, again act on a fresh portion of the said bands.

Any other gripping device could be employed with the object of obtaining the desired result, that is to say the intermittent drive in equal steps (but which can be varied at will when passing from one manufacture to another).

It is for example possible to provide, as shown in FIGS. 16 and 17, that the moving member 26a of the jack 26 carries out on the one hand a direct drive in both directions on the gripping member 27 (with its gripping elements 28a and 29a, constituted by a cooperating set of rollers and a knife, and the electromagnet 39) and on the other hand a drive in a single direction by means of a chain 40 carried by the arm 26b of the moving member 26a and of a free wheel 40a of the roller 31. Since the rollers 30 and 31 provide a drive for the band 8, the upper rollers 30 and lower rollers 31 are made respectively of flexible material (such as rubber) and of a hard material (such as steel) so as to insure on the one hand a taking-up of play due to wear and an exact adjustment of the drive (since the diameter of the hard roller remains constant).

Following this, whatever form of embodiment may be adopted, a machine can be set up to form and eventually cut-out various articles, in particular boxes, from flexible bands, which are for example transparent or translucent.

Such a machine operates in the following manner.

After the various devices have been placed in position and the working tools and adjustment of the masks in the heating device CH have been prepared, each working cycle comprises the following operations:

The forward movement of the two bands 1 and 2 (the second carrying when so desired, inscriptions as can be seen in FIG. 16) by one step by means of the traction device Ti actuated by the jack 26, the setting of the exact length of the step being completed eventually by means of a photo-electric cell (not shown) in front of which pass the inscriptions or reference marks arranged on the band 2, and acting on the traction device Ti;

The simultaneous lift of the lower plates 14 of the devices for forming welding, and cutting-out, for example by distribution of compressed air as indicated in FIG. 16 by means of supply conduits 37 and return conduits 38 for compressed air, followed by the vacuum to carry out the forming, the high-frequency for the welding and the punching-out pressure being applied for example independently, for a period which can be regulated by timing mechanisms (not shown), depending on the article manufactured.

Downward movement of the lower plates of the device for forming, welding and cutting-out, also preferably by the effect of a parallel distribution of a compressed fluid such as air;

At the same time as the operations of forming, welding, and cutting-out, the operation of filling takes place (when such is required) in the filling zone C, and also of course (as explained above) the return of the moving portion of the traction element Ti to the position from which it is ready to start its tractive operation again and a fresh cycle begins.

It will be observed that in the form of embodiment of

the drawing device Ti shown in FIGS. 16 and 17, when the moving member 26a (on which is fixed the gripping member 27) of the jack 26 moves towards the right, taking with it the gripping elements 28a and 29a urged against each other and in consequence drawing the band or bands 8 in the direction of the arrow *f*, it causes by the action of its arm 26b on the chain 40, the rotation of the wheel 40a and in consequence that of the roller 31 which facilitates the ejection of the band 8 on the downstream side of the gripping elements, and avoids any choking between these elements and the rollers 30 and 31; when the moving member of the jack 26 moves towards the left, taking with it the gripping elements (without acting on the band since the gripping elements are then moved away by the electro-magnet 39) from the position shown in FIG. 16 to the position of FIG. 17, from which they again draw the band, it is without action on the roller 31 since the free wheel 40a does not provide any drive when the chain 40 is displaced in this direction.

This operation is such that when the respective positions of the various stations along the bars such as 9 have been suitably set by using the rule 35 (see FIG. 16), after each fresh movement of the band there is produced the ejection of a box which will have previously passed through the various successive treatments corresponding to the number of stations employed.

A machine of this kind has a large number of advantages as compared with machines of the type in question which already exist;

The possibility of manufacturing objects of different shapes and sizes, by virtue of the fact that the various elements of this machine are easily controllable as to position and that the working tools are readily interchangeable;

That of insuring however a minimum overall size, since no space has been wasted;

Also that of enabling the losses of raw material to be reduced to a minimum and in many cases, such as particularly the application to receptacles or objects of rectangular shape, of eliminating all losses of material due to waste at the cutting-out stage;

That of insuring that the whole machine is fairly light; And that of enabling the lower parts of the plates to be freed so as to ensure easy ejection;

That of being able to work, in the case of certain forms of embodiment, solely by compressed air with the exception of the electric current required for heating and welding and for the regulating apparatus.

The first of the advantages referred to above is due in particular to the mounting of the various stations of the machine, and to the possibility of adjustment which results from this. By means of this possibility of adjustment, it is possible to interchange the various operations or again to double certain operations, for example two stages of forming, cutting-out or welding, either by arranging the similar apparatus or stations side by side and/or behind each other. Similarly, certain of these operations can be eliminated.

This results in facility of adaptation of the machine in question to the most diverse kinds of manufacture in a very short time, which renders the machine universal with resulting advantage from the economic point of view, even in the case of small and medium sizes.

Thus, apart from the possibility of manufacturing boxes of round, rectangular or other shape, it is also possible in a more simple manner to prepare cellular bands 1b such as those shown in FIG. 8 for example, intended to float, or again bands 1c provided with various hollow and relief portions such as shown in FIG. 9.

In the case of boxes, it is possible by proceeding to suitable cutting-out of the bands or at least of one of the two bands, to make lids with handles 34 such as shown in FIG. 10 (boxes 7a).

FIG. 11 shows that boxes 7b can be formed by two hollow portions isolated from each other and obtained from two separate bands.

The same method may be applied to the manufacture of all objects, FIG. 12 showing the application to bottles 7c.

By starting with a similar arrangement, it is also possible to produce cellular bands 1d comprising entirely hollow and closed portions as shown in FIG. 12, such bands 1d being suitable for example for the manufacture of floats or all other members intended to be made light with respect to an ambient fluid.

The articles of FIGS. 11, 12 and 13 may be simply produced, as shown in FIG. 18, by providing for the station PF two moving elements of the type 14, 5 which may be moved away from or brought closer to the bars 9 transversely to the two bands 1 and 2 which are both treated so as to produce a cell in each, the welding and the cutting-out of the shaped bands 1a and 2a being carried out as in the case of the boxes 7 of FIGS. 1 and 2.

A further possibility is shown in FIG. 14 which shows a teacloth in which, by suitable treatment at a forming station PF, there has been cut out or obtained by deformation of the band, a kind of embroidery.

Finally, starting with a number of bands, for example 3, various objects such as wallets 33 can be formed. FIG. 15 shows that one of the bands 1, unwound from a roll 3, is first given a surface treatment at 32 in a shaping station PF so as to obtain a decorative surface effect. Then the two other bands 2a and 2b, delivered from the corresponding reels 4a and 4b, are utilized to form the pockets of the wallet 33.

A large number of other applications can readily be envisaged while remaining within the scope of the invention.

As will be readily understood and as furthermore results already from the preceding description, the invention is not in any way limited to those methods of application or to those forms of embodiment of its various parts which have been more particularly considered; on the contrary, the invention includes all their possible alternative forms.

What we claim is:

1. A machine adapted to form various articles from a flexible band and comprising longitudinal supporting means, at least two working stations each adapted to perform, when operated during a given time period, a predetermined forming step on said band, means for securing

each of said working stations in an adjustable position along said longitudinal supporting means, actuating means for rendering said working stations simultaneously operative, and driving means for pulling said band step by step, between successive operations of said actuating means, along said supporting means through said working stations, said drawing means comprising two cooperating elements relatively movable in opposite directions perpendicular to said band between a first position in which said elements grip said band and a second position in which said elements are inoperative relative to said band, means for displacing both said cooperating elements to and fro along said longitudinal supporting means between a pair of precisely determined locations, at least one location in said pair being adjustable, and means for maintaining said cooperating elements in said first position when said elements are moved along said longitudinal supporting means from a first to a second location in said pair and in said second position when said elements are moved along said longitudinal supporting means from said second to said first location in said pair.

2. A machine as claimed in claim 1 wherein one of said stations is a welding station.

3. A machine as claimed in claim 1 wherein one of said stations is a welding station and another of said stations is a cutting-out station.

4. A machine as claimed in claim 1 wherein at least one of said stations comprising a first portion generally in the shape of a gantry and adapted to be fixed in adjustable manner on said longitudinal supporting means, and a second portion including a movable plate of annular shape movable transversely to the direction of motion of said band, and working tools on said first and second portions, said actuating means being operatively associated with the movable plate for controlling said drawing means.
